CLAIM

The ornamental design for a footwear sole, as shown and described.

DESCRIPTION

This application is related to U.S. Design patent application Ser. No. 29/619,175, U.S. Design patent application Ser. No. 29/641,181, and U.S. Design patent application Ser. No. 29/641,188 filed concurrently herewith and entitled "Footwear Sole," the entire disclosures of which, including the figures, are hereby expressly incorporated by reference herein.

FIG. 1 is a perspective view of a footwear sole in accordance with an embodiment of the ornamental design;

FIG. 2 is a front elevational view of the footwear sole in accordance with the embodiment;

FIG. 3 is a back elevational view of the footwear sole in accordance with the embodiment;

FIG. 4 is a left side elevational view of the footwear sole in accordance with the embodiment;

FIG. 5 is a right side elevational view of the footwear sole in accordance with the embodiment;

FIG. 6 is a top plan view of the footwear sole in accordance with the embodiment; and,

FIG. 7 is a bottom plan view of the footwear sole in accordance with the embodiment.

Broken lines are used to show unclaimed environment only and form no part of the claimed design.

1 Claim, 6 Drawing Sheets
